UNITED STATES PATENT OFFICE.

JAMES M. HIMES, OF WASHINGTON, DISTRICT OF COLUMBIA.

WINDOW-VENTILATOR.

1,093,415.

Specification of Letters Patent. Patented Apr. 14, 1914.

Application filed November 19, 1913. Serial No. 801,976.

To all whom it may concern:

Be it known that I, JAMES M. HIMES, a citizen of the United States, resident of Washington, District of Columbia, have 5 made a certain new and useful Invention in Window-Ventilators; and I declare the following to be a full, clear, and exact description of the same, such as will enable others skilled in the art to which it appertains to make and use the invention, reference being had to the accompanying drawings, and to letters or figures of reference marked thereon, which form a part of this specification.

15 Figure 1 is a vertical transverse section of the invention as applied with the lower sash raised, and the invention placed thereunder. Fig. 2 is an inside face view of the invention. Fig. 3 is a section on the line 3—3, 20 Fig. 1. Fig. 4 is a vertical transverse section of the invention as applied within a slot of the lower window sash rail.

The object of the invention is to provide an improved ventilating appliance for windows, and the invention consists in the novel construction and combinations of parts as hereinafter set forth.

In the accompanying drawings illustrating the invention, the numeral 1, designates 30 the lower rail of the lower window sash to which the invention is usually applied, said rail having therein a longitudinal slot 2. Fitting within the slot 2 in such a manner as to be preferably flush with the sides of 35 said rail is a metallic ventilating frame 3, composed of a plurality of continuous metal strips, each strip being bent to form a plurality of oppositely disposed angles usually of about sixty degrees each, said strips being 40 parallel with and separated from each other to form a series of overlying zig-zag ventilating passages. The metal strips are each composed of four leaves having three 45 bends, the outer of said leaves having a downward and outward inclination in opposite directions from within the slot 2 to 50 shed water and dust, and the two inner leaves forming a channel, usually having bottom perforations 4 to allow escape of any water that may find its way therein. The 55 metal strips are rigidly connected to end walls 5, 5, forming a unitary frame, said frame having at one side outward projecting flanges 6, 6, which will abut against the side of the sash rail when the frame is inserted within the rail slot to limit the in-

ward movement of the frame. A cover plate 7 is then placed upon the inside of the sash rail over the ventilating frame and over the rail slot, said plate having a bearing against said flanges to secure the frame in place, suitable securing means or screws 8 being provided to hold the cover plate to the sash rail. Upon the outside, a screen cover 9 is placed over the ventilating frame 65 and over the rail slot, to prevent admission of insects or other objectionable matter.

The cover plate 7 is provided at its ends with flat pockets 10, of sufficient length to receive the leaf sections 11 of sliding doors 12, the upper and lower edges of which have movement in longitudinal channels 13 of said plate. Usually two leaf sections are provided for each door, these sections being of about the same size as the pocket, and 75 being slidable upon each other, so that when they are moved outward, as in opening the ventilating passage-way more or less as may be required, they will be received to such extent as may be necessary in the pockets 80 10 at the ends of the cover plate. When the door leaves are moved to the extent of movement allowed outward, to entirely open the ventilating passage-ways, the leaves will be entirely received within the end pockets, 85 out of sight. The doors are provided with operating knobs 14, and with outer or end flanges 15, serving to connect the sections when pulled out in series from the pockets 10.

In buildings already completed, the invention may be applied to an oblong frame 16, to be placed below the lower sash, the lower rail of which is brought down upon the frame to hold it in position, as shown 95 in Fig. 1 of the drawings.

What I claim is:—

1. In a window ventilator, an outer carrying frame having a longitudinal slot, a ventilator frame fitting within said slot and 100 provided with a series of overlying zig-zag air passages, and an inner vertical cover frame for said slot having end pockets, and adjustable vertical door leaf sections engaging said pockets and each other and sliding 105 upon each other to close said passages to a regulated degree.

2. In a window ventilator, an outer carrying frame having a longitudinal slot, a ventilator frame fitting within said slot and 110 provided with a series of continuous overlying zig-zag bent metal strips parallel with

and spaced apart from each other to provide zig-zag air passages, each of said strips having a central inner channel and outwardly and downwardly inclined leaves at the sides, said channel having a perforated bottom, and an inner vertical cover frame for said slot having end pockets and adjustable vertical door leaf sections engaging said pockets and each other and sliding

upon each other to close said passages to a ¹⁰ regulated degree.

In testimony whereof I affix my signature, in presence of two witnesses.

JAMES M. HIMES.
